FLUORESCENT LAMP

Everett B. Huff, San Francisco, Calif.

Application August 29, 1946, Serial No. 693,742

2 Claims. (Cl. 315—102)

1

The present invention relates to improvements in fluorescent lamps, and its principal object is to provide means for economically operating a relatively high-voltage fluorescent lamp on a direct current obtained from a series of dry cells.

For this purpose it is particularly proposed to use two different voltages for starting and for operating the lamp, a relatively low voltage being used for starting the lamp, and a higher voltage for continuing the operation of the lamp.

The use of a relatively low voltage for starting the lamp is of particular advantage insofar as it lengthens the life of the filament, since a higher voltage would tend to burn out the filament in a short time.

The use of a higher voltage for continuing the operation of the lamp has the advantage of reducing the amperage needed for operating the lamp and thereby extends the life of the battery of dry cells. It has the further advantage of increasing the tension between the electrodes so as to make it possible to start the lamp by energizing one electrode only.

It is further proposed in the present invention to provide a simple means for stopping operation of the lamp which consists in the simple expedient of momentarily bypassing the lamp current.

And finally, it is proposed to provide certain structural features and electrical connections whereby the lamp and the electrical operating means are combined into a simple, attractive and portable unit.

Further objects and advantages of my invention will appear as the specification proceeds and the new and useful features of the same will be fully defined in the claims attached hereto.

The preferred form of my invention is illustrated in the accompanying drawing forming part of this application, in which:

Figure 1 shows a side view of my assembled fluorescent lamp assembled in a portable unit;

Figure 2, a top plan view of a plate carrying the various electrical connections;

Figure 3, a bottom plan view of the same; and

Figure 4, illustrating a wiring diagram.

While I have shown only the preferred form of my invention, it should be understood that various changes or modifications may be made within the scope of the claims attached hereto without departing from the spirit of the invention.

Referring to the drawing in detail, my invention comprises in its principal features a box 1 containing a series of batteries, a plate 2 super-

2

imposed on the box for carrying the various electrical connections, and a fluorescent tube 3 mounted above the plate.

The fluorescent tube is of commercial standard type, one of the objects of the invention being to make a relatively large tube available for operation by a series of dry batteries.

My invention was particularly developed in connection with a standard fourteen or twenty 10 watt tube, fourteen inches long and one and one-half inches in diameter.

The box 1 contains a series of dry cells, preferably arranged in three units 4, 5 and 6 connected in series by conductors 7 and 8, the first two 15 units 4 and 5 having a voltage of forty-five volts each, making a total of ninety volts, and the third carrying sixty volts, so that the aggregate voltage is one hundred and fifty volts.

These batteries are connected into the tube 20 circuit as follows: referring to the wiring diagram of Figure 4:

The positive terminal 10 of the second battery 5 connects, through wire 11 and through one side 12 of a single-pole, double-throw switch 13, with one electrode or filament 14 of the tube, which latter is connected to the negative terminal 15 of battery 4.

Thus, upon a momentary closing of the switch at 12, a current will flow through the filament 25 14, under pressure of ninety volts, energizing the filament. This is the starting circuit.

The positive terminal 16 of battery 6 is connected, through wire 17, a resistance 18 of preferably fifteen hundred ohms, electrode 19 of the tube, the gas in the tube, and electrode 14 to the 30 negative terminal 15 of battery 4.

This is the operating circuit for lighting the tube, and operates on one hundred and fifty volts.

This relatively high voltage is sufficient to 35 bridge the gap between the two electrodes on the energizing of only one of them, and I have found from experience that it will operate a standard fourteen watt tube, fourteen inches in length and one and one-half inches in diameter, with a resistance of fifteen hundred ohms included in the circuit, at a current consumption of approximately forty milliamperes, which insures a long life for the battery.

For extinguishing the light, I use a shunt or 40 by-pass 20 across the two electrodes 19 and 14, the by-pass including the other side 21 of the double-throw switch 13, so that, upon momentary closing of the switch at 21, the current of the main operating circuit is made to by-pass the tube. By the time the switch 13 opens again,

the tube has become inoperative for carrying current and will remain inactive until started again by operation of the switch at 12.

The physical arrangement of the wiring system is illustrated in Figures 1, 2 and 3. The plate 2, which is of insulating material, and which preferably is rectangular in form and slightly larger than the box 1, is mounted on top of the latter, in slightly spaced relation thereto, and is anchored in place by means of two screws 22.

Connection with the battery terminals is made through a conventional, centrally located prong and socket arrangement, in which the positive terminals 16 and 10, and the negative terminal 15 are represented as shown.

The switch 13 is shown in the form of a leaf spring 23 disposed underneath the plate and centrally anchored thereto, as at 24. The two free ends of the leaf spring are operated by means of push buttons 25-26 slideable in the plate for cooperation with the contacts 12 and 21 respectively.

The starting circuit may be traced as comprising the battery terminal 10 (90 volts), the wire 11, switch contact 12, switch post 24, wire 27, the filament at the right end of the tube, the wire 28 back to battery terminal 15. This circuit is closed by momentary pressure on the switch button 25.

The main circuit comprises the battery terminal 16 (150 volts), wire 17 including the resistance 18, the two electrodes 19 and 14 of the tube, and wire 28 leading back to the negative terminal 15 of the battery.

The by-pass connects the left-hand electrode 19 through wire 20, contact 21, leaf spring 23 of the switch and wire 27 with the negative terminal of the battery. This by-pass is closed by operation of switch button 26.

The tube 3 is mounted in two brackets 30 rising from the ends of the plate, the brackets being of conventional type and suitably equipped for bringing the tube electrodes into the circuit.

The operation of my device is very simple. For starting, the operator momentarily presses down on button 25 which energizes filament 14 at ninety volts and starts the lighting at one hundred fifty volts.

For turning off the light, the operator momen-

tarily presses down on button 26 which bypasses the current and automatically extinguishes the light.

I claim:

1. In a fluorescent gas discharge system, a battery comprising a plurality of cells connected in series, a fluorescent tube having an anode and a filamentary emissive cathode, a starting circuit comprising unloaded wires connecting the cathode to low and high sides of the battery respectively for preheating the cathode and a switch in the circuit, means independent of the starting circuit connecting the anode and the cathode to the battery to form a circuit for lighting the tube automatically subsequent to the preheating of the cathode, a resistance in said circuit, a shunt for the tube and made to connect the resistance, the anode and the cathode in series with the battery, and a switch in the shunt operable for momentary closing, the shunt having sufficient conductivity to by-pass current from the tube for extinguishing the latter, and the total resistance of the shunt circuit being sufficient to prevent heating of the cathode effective for starting purposes.

2. A fluorescent gas discharge system as defined in claim 1, in which the battery has a pressure of approximately 150 volts, the tube a capacity of approximately between 14 and 20 watts and the resistance is of the value of approximately 1500 ohms, while the starting circuit is connected to the battery at a pressure of approximately 90 volts.
